Webb Harding of Cambridge, Mass.
Letters Patent No. 121906 - Dated March 1st 1887.
Design for a Macaroni Spoon.

Des. 1906

The schedule referred to in these Letters Patent and making part of the same.

To all whom it may concern:

Be it known that I, Webb Harding, of Cambridge in the County of Middlesex and State of Massachusetts, have invented a new and useful design or form for a macaroni spoon; and I do hereby declare that the following, taken in connection with the drawings which accompany and form part of this specification, is a description of my invention sufficient to enable those skilled in the art to practise it.

My new form or design for a macaroni spoon is represented in the accompanying drawings.

Figure 1, showing the same in top view, and

Figure 2, in side elevation.

A spoon having a bowl, a. of proportions and contours very similar to the common spoon, has deep serrations or spaces b. cut or formed in its edges along the sides and point or forward end thereof, such spaces leaving the pointed and curved teeth c. as seen in the drawings. The serrations b. do not extend to the whole depth of the bowl.

I claim therefore, the design or form of macaroni spoon as shown and described.

Witnesses:

J. B. Crosby
Julius L. D. Sullivan.

Webb Harding.
